UNITED STATES PATENT OFFICE

CARL J. MEEK, OF ST. LOUIS, MISSOURI, ASSIGNOR TO UNITED SHOE MACHINERY CORPORATION, OF PATERSON, NEW JERSEY, A CORPORATION OF NEW JERSEY

MACHINE FOR OPERATING UPON SOLES

Application filed January 29, 1929. Serial No. 335,851.

This invention relates to machines for operating upon soles and is illustrated as embodied in an insole slashing machine of the type disclosed in United States Letters Patent No. 958,029, granted May 17, 1910, upon application of W. C. Stewart.

The machine disclosed in the Letters Patent referred to is adapted to make a plurality of slashes extending transversely across an insole in the vicinity of its ball portion for the purpose of making the sole more flexible in this portion than it otherwise would be. To this end the patented machine comprises a fixed work support, a reciprocating slashing knife, a work-clamping roll and a feed roll for engaging opposite sides of a sole and feeding the sole across the work support and past the knife, and a bending roll for bending the sole toward the work support preparatory to operation upon the sole by the knife.

In order to adapt a machine of this type for operation upon ribbed insoles such, for example, as Economy insoles without flattening out or injuring the sewing rib, and in accordance with one feature of the present invention, the illustrated machine comprises a roll constructed and arranged to have peripheral engagement with the face at the ribbed side of a sole between oppositely disposed portions only of the rib, and means for supporting the sole and co-operating with the roll to feed the sole into position to be operated upon.

In the illustrated machine, the roll for engaging the ribbed side of the sole inside of the rib is located in front of the slashing knife and is arranged to turn idly to co-operate with a positively driven feed roll arranged to engage the unribbed side of the sole. In accordance with the present invention the idle roll, hereinafter referred to as the work-clamping roll, is made short enough to engage the insole between the portions of the sewing rib at the opposite lateral margins of the narrowest portion of the sole, that is, along the shank of the sole, and furthermore, this roll is mounted with provision for endwise movement and it is engaged by a spring arranged normally to hold the roll in a central position while permitting it to yield endwise or axially in either direction as may be necessary in or-

der for the roll to accommodate itself to the space between the oppositely disposed portions of the rib in the shank portions of soles having different degrees of swing. Moreover, as illustrated, the bending roll is also made short enough to insure its engagement between the opposed portions of the rib so that it will perform its bending operation without having any tendency to flatten out or injure the rib.

The invention will be explained with reference to the accompanying drawings, in which

Fig. 1 is a vertical sectional view of so much of an insole slashing machine as is necessary to illustrate the application of the present invention thereto;

Fig. 2 is a perspective view of the slashing, feeding and bending instrumentalities of the machine, illustrating their mode of operation upon a ribbed insole of the Economy type;

Fig. 3 is a view in front elevation of the parts of the machine shown in Fig. 1; and

Fig. 4 is a plan view of a ribbed insole of the Economy type illustrating conventionally the relation to the sole of the work-clamping and bending rolls.

The invention is shown in the drawings as embodied in an insole slashing machine like that disclosed in Letters Patent No. 958,029 hereinbefore referred to. The illustrated machine, in common with the patented machine, comprises a head frame 10, a vertically reciprocating cross-head 12, a work rest 16 for the portion of the work being operated upon by the knife, a driven lower feed roll 18 carried by a swinging feed roll frame 20, a work-clamping roll 22 carried by a frame 24 pivoted to the feed roll frame 20, and a deflecting or bending roll 26 carried by a swinging frame 28. Except in particulars hereinafter described, the above-named parts, together with their actuating mechanism and all other parts illustrated in the drawings and not hereinafter specifically referred to, have substantially the same construction, arrangement and mode of operation as that of corresponding parts in the machine of the patent above referred to and reference may be had to such patent for details of construction and opera-

tion not herein specifically described. To assist in understanding the present invention, however, it is herein stated that the work-clamping frame 24 is in the form of a yoke 5 the arms 30 of which are pivoted at 32 to the swinging feed roll frame 20 so that the clamping roll 22 may be moved away from the feed roll 18 to facilitate introduction of the work into the machine, the clamping roll frame 24 10 being normally held in position for the clamping roll 22 to co-operate with the feed roll 18 by means of a spring 34. It should furthermore be understood that the bending roll frame 28 is also in the form of a yoke the arms 36 of which are adapted to support a work bending roll 26.

In the machine shown in the drawings, in order to insure that the work-clamping roll 22 and the work bending roll 26 shall perform 20 their respective functions without flattening or otherwise injuring any portion of the sewing rib of an insole these rolls are constructed and mounted as will now be described.

The work-clamping roll 22 is made of such 25 width as to engage the ribbed surface of an insole like that shown at S in the drawings without overlapping or engaging the oppositely disposed portions of the sewing rib at the lateral margins of the sole even at the shank portion where the sole is of minimum 30 width and where the opposed portions of the sewing rib are relatively close together. The length of the clamping roll 22 relatively to the width of the sole between the opposed 35 portions of the sewing rib is best shown in Fig. 4 upon an inspection of which it will be apparent that the roll 22 will freely engage between the opposed portions r, r of the rib R at the shank of the sole without overly- 40 ing the rib at either edge of the sole so as to have any tendency to flatten or injure the rib. To facilitate effective feeding of the sole, however, the roll 22, as herein shown, is made of a width substantially equal to the space 45 between the oppositely disposed portions of the sewing rib at the narrowest portion of the shank of the sole. As shown, the work-clamping roll 22 is mounted to turn idly upon a rod 40 which is fixedly secured at its ends 50 in the arms 30 of the clamping roll frame 24.

In most insoles, the center line of the forepart of the sole is disposed at more or less of an angle to, or is laterally offset from, the center line of the heel portion of the sole, 55 this angular or offset disposition of the forepart and heel part being customarily referred to as the "swing" of the sole. To insure that the soles shall flex or bend in the required manner after being slashed it is desirable that 60 the slashes shall be made parallel to one another and that they shall extend across the sole substantially at right angles to the center line of the forepart. It is desirable, therefore, 65 that the sole shall be introduced into the slashing machine with the center line of the fore-

part of the sole at right angles to the blade of the slashing knife and to the axis of the work-clamping and bending rolls and that the insole shall be fed through the machine in a direction at right angles to the blade of the slashing knife, it being undesirable to turn or swing the sole as it is fed since such turning or swinging would change the desired location of the slashes in the sole. Accordingly, 70 it will be apparent that while the work-clamping roll 22 is short enough to avoid engagement with the portions of the rib at the opposite edges of the sole at the start of the slashing operation when the said roll is located as shown in Fig. 4 near the ball portion 80 of the sole, and while the roll is capable also of engaging between the ribs at the narrowest portion of the shank, nevertheless, if there is any appreciable amount of swing to the sole, the central portions of the shank and forepart will be out of line with each other and the shank will be offset relatively to the clamping roll. Accordingly, as the sole is being fed in the general direction of the center line of its forepart the rib at one side or the other of the shank will be engaged by the end of the roll 22 as the sole continues its forward movement through the machine.

In order to insure that the roll 22 will not ride over the portion of the rib engaged thereby with consequent danger of flattening or injuring it, the roll 22, as herein shown, is mounted with provision for endwise movement upon the rod 40. As shown, the roll 22 is normally maintained yieldingly in a central position upon the rod 40 by means of a leaf spring 50 secured at its upper end by screws 52 to a fixed portion 54 of the head frame 10 and the lower end of which engages within an annular groove 56 in the periphery of the clamping roll 22, the spring 50 being arranged to yield sidewise so as to permit endwise sliding movement of the roll on the rod 40. By thus mounting the roll 22 so that it is capable of sliding in either direction upon the rod 40, the roll is rendered capable of accommodating itself to the space between the portions of the rib at the opposite edges of the narrow shank portion of the sole irrespective of the degree of swing of the sole 105 or the amount of offset of the shank portion of the sole.

To provide for sufficient bearing between the spring 50 and the sides of the slot 56 in the roll 22 there is formed in the lower end of the spring a segmental notch 58 shaped to conform to the curvature of the bottom of the slot in the roll. In order that the roll 22 may be readily moved toward and from the lower feed roll 18 as the frame 24 is swung about its pivotal connections with the frame 36 the spring 50 is constructed and arranged to yield readily in directions at right angles to the axis of the roll 22 as well as in directions parallel to the axis of the roll, this construction 110 115 120 125 130

enabling the spring to yield forwardly as required by upward movement of the roll 22. To this end, the illustrated spring 50 is twisted as indicated at 60 to provide an upper portion 62 disposed transversely at right angles to the lower portion of the spring, which portion 62 is capable of bending to permit the required forward yielding of the spring. When a sole is being operated upon the roll 22 occupies the position shown in Fig. 1 with the curved bottom of the slot 56 located in the notched lower extremity of the spring 50. It will be noted that while the bottom of the slot in the roll 22 moves out of a position in which it conforms to the curve of the segmental notch 58 the lower extremity of the spring 50 nevertheless remains engaged between the side walls of the slot in the roll 22 so that the roll is at all times maintained under the influence of the spring.

The illustrated work bending roll 26 is also made of the same length as the work-clamping roll 22 to insure engagement of the work bending roll between the opposed portions of the rib R, the bending roll 26 being mounted to turn idly upon a rod 42 which is fixedly secured at its opposite ends to the arms 36 of the bending roll frame 28. The bending roll 26 is maintained in a predetermined position upon the rod 40 by means of spacing sleeves 44, 44 on the rod 42, one at either side of the roll 26.

When a sole is to be inserted in the machine the clamping roll 22 and the bending roll 26 each occupies positions in which the rolls are separated from the lower feed roll 18 and from the work rest 16, respectively, by distances substantially greater than the thickness of the sole to be operated upon, the rolls having been moved into these positions by upward swinging movements of the frames 24 and 36. After the sole has been passed between the rolls 18 and 22 and between the work rest 16 and the bending roll 26 and has been advanced into position for the making of the first slash, the frames 24 and 36 are swung downwardly to position the rolls 22 and 26 in co-operative relation to the roll 18 and the work rest 16 respectively and the machine is set in operation under power. Thereupon, the slashing knife 14 is reciprocated rapidly to cut a series of slashes in the ribbed surface of the insole between the opposed portions of the sewing rib. During the operation of the slashing knife the sole is fed forwardly step-by-step, the machine being timed so that each slash is made during a period of rest between successive increments of feed movement. In operating upon an insole in which there is any substantial amount of swing or edgewise offset of the forepart relatively to the heel and shank portions the sole is fed through the machine in a direction parallel to the center line of the forepart of the sole. Consequently the center line of the

heel and shank portions of the sole is inclined or offset with respect to the direction of feed because of the swing of the sole and the portions of the rib which extend along opposite sides of the shank are also inclined with respect to the direction of feed. It will be apparent, therefore, that as the sole advances through the machine the inner side of the rib at one side of the shank is liable eventually to be brought into engagement with the adjacent end face of the clamping roll. It will also be apparent that the lengthwise inclination of the portion of the rib engaging the clamping roll will be such that the rib will exert a cam action on the roll, causing the roll to slide on the rod 40 in a direction away from the rib so that the roll will automatically accommodate itself to the space between the ribs at the shank of the sole, the roll keeping within this space so that it will not ride over the rib and consequently will not flatten or otherwise injure it. Obviously, if there is no swing or edgewise offset to the sole which is being operated upon, the short clamping roll 22 will ride between the portions of the rib at opposite sides of the shank without having to be displaced endwise from its normal position inasmuch as the roll is normally held in a central position in line with the bending roll 26.

As hereinbefore mentioned, the slashes do not ordinarily extend rearwardly of the ball portion of the sole. After the last slash has been made the operation of the machine under power is automatically stopped, whereupon the operator separates the clamping roll 22 and the bending roll 26 from the feed roll 18 and from the work rest 16, respectively, and removes the sole from the machine by a movement toward the operator, in other words, backing the sole out of the machine. It will be apparent, therefore, that the narrow shank portion of the sole is never moved into engagement with the bending roll 26 which is located forwardly of the slashing knife and inasmuch as the portion of the sole forwardly of the shank is of sufficient width so that there is no danger of the portions of the rib engaging the short bending roll 26 it is unnecessary to provide for endwise movement of the bending roll on its supporting rod 42 in order to insure against danger of injury to the rib by the bending roll.

Having described my invention, what I claim as new and desire to secure by Letters Patent of the United States is:

1. In a machine for operating upon ribbed soles, in combination, an operating instrumentality, and means for feeding a sole to the operating instrumentality comprising a roll constructed and arranged to have peripheral engagement with the face at the ribbed side of the sole between oppositely disposed portions only of the rib, said roll being of

- substantially the same width as the space between said oppositely disposed portions of the rib at the narrowest part of the shank of the sole to facilitate effective feeding of the sole.
2. In a machine for operating upon ribbed soles, in combination, a roll constructed and arranged to have peripheral engagement with the face at the ribbed side of a sole between oppositely disposed portions only of the rib, and means for supporting the sole and co-operating with said roll to feed the sole into position to be operated upon.
3. In a machine for operating upon ribbed soles, in combination, a roll constructed and arranged to engage the ribbed face of a sole, between oppositely disposed portions of the rib, and a mounting for the roll enabling it to adjust itself axially to accommodate itself to the spaces between oppositely disposed portions of the ribs of soles having different degrees of swing.
4. In a machine for slashing ribbed soles, in combination, a slashing knife, and means for feeding a sole to the knife comprising a roll constructed and arranged to engage the ribbed side of the sole inside of the rib only whereby the sole may be fed without danger of injury to the rib.
5. In a machine for slashing ribbed soles, in combination, a slashing knife, and means for feeding a sole to the knife comprising a roll constructed and arranged to engage the ribbed side of the sole along the shank without engaging the ribs, said roll being adjustable axially to adapt it for use in connection with soles having different degrees of swing.
6. In a machine for slashing ribbed soles, in combination, a slashing knife, and means for feeding a sole to the knife comprising a roll constructed and arranged to engage the ribbed side of the sole along the shank without engaging the ribs, said roll being mounted for endwise movement enabling it to accommodate itself to the spaces between the ribs at the shank portions of soles having different degrees of swing.
7. In a machine for slashing ribbed soles, in combination, a slashing knife, a roll constructed and arranged to engage the ribbed side of a sole between the ribs only, and a feed roll for engaging the unribbed side of a sole to feed the sole to the knife.
8. In a machine for slashing ribbed soles, in combination, a slashing knife, a driven feed roll for engaging the unribbed side of a sole, and an idle roll for engaging the ribbed side of the sole and co-operating with the driven roll to feed the sole to the knife, the idle roll being short enough to engage the sole between the ribs only, and a mounting for the idle roll enabling it to adjust itself axially to accommodate soles having different degrees of swing.
9. In a machine for slashing ribbed soles, in combination, a slashing knife, a feed roll for engaging the unribbed side of a sole, a second roll constructed and arranged to engage the ribbed side of the sole between the ribs only and to co-operate with the first roll to feed the sole to the knife, the second roll being capable of endwise adjustment to accommodate itself to the spaces between the ribs of soles having different degrees of swing, and yielding means normally effective to hold the roll in a predetermined endwise relation to the first roll.
10. In a machine for slashing ribbed soles, in combination, a slashing knife, a feed roll for engaging the unribbed side of a sole, a rod extending parallel to the feed roll, a tubular roll mounted to turn on the rod and shaped to engage the ribbed side of the sole between the ribs only, said roll being capable of moving endwise on the rod to accommodate itself to the spaces between the ribs of soles having different degrees of swing, and yielding means tending to hold the tubular roll in a central position on the rod.
11. In a machine for slashing ribbed soles, in combination, a slashing knife, a feed roll for engaging the unribbed side of a sole, a second roll constructed and arranged to engage the ribbed side of a sole between the ribs only and to co-operate with the first roll to feed the sole to the knife, said roll being capable of endwise movement enabling it to accommodate itself to spaces between the ribs in soles having different degrees of swing, and a spring arranged to be stressed by endwise movement of the roll in either direction for holding the roll normally in a predetermined endwise relation to the first roll.
12. In a machine for slashing ribbed soles, in combination, a slashing knife, means for feeding a sole to the knife comprising a feed roll constructed and arranged to engage the ribbed side of a sole between the ribs only, said roll being capable of endwise movement to accommodate itself to soles having different degrees of swing and having an annular groove in its periphery, and a leaf spring projecting into the groove in the feed roll for holding the roll yieldingly in a predetermined position of endwise adjustment.
13. In a machine for slashing ribbed soles, in combination, a slashing knife, means for feeding a sole to the knife comprising a short feed roll adapted to engage the ribbed side of a sole between the ribs only, and a second short roll also arranged to engage the ribbed side of the sole only between the ribs for flexing the sole preparatory to operation thereon by the slashing knife.
14. In a machine for slashing ribbed soles, in combination, a slashing knife, a support for the sole while it is being slashed, means for feeding the sole past the knife comprising

ing a short feed roll arranged to engage the ribbed side of the sole between the ribs only and in front of the knife, and a second short roll arranged to co-operate with said support at a point beyond the knife to flex the sole preparatory to operation thereon by the knife.

In testimony whereof I have signed my name to this specification.
